UNITED STATES PATENT OFFICE.

RALPH B. HARTSOUGH, OF MINNEAPOLIS, MINNESOTA.

TRACTOR.

1,262,488.

Specification of Letters Patent.

Patented Apr. 9, 1918.

Application filed January 22, 1916. Serial No. 73,523.

To all whom it may concern:
Be it known that I, RALPH B. HARTSOUGH, a citizen of the United States, residing at Minneapolis, in the county of Hennepin and State of Minnesota, have invented certain new and useful Improvements in Tractors; and I do hereby declare the following to be a full, clear, and exact description of the invention, such as will enable others skilled in the art to which it appertains to make and use the same.

My invention relates to tractors, and more particularly of the type disclosed and claimed in my pending application, Serial Number 35,191, filed June 21st, 1915, and entitled "Tractor". In the drawings of my said application, the main longitudinal member of the tractor frame is in the form of a long and quite large and heavy tubular arm. The present invention consists in utilizing this tubular arm as an exhaust muffler for the internal combustion or explosive engine of the tractor.

In the accompanying drawings which illustrate the invention, like characters indicate like parts throughout the several views.

Referring to the drawings:

Figure 1 is a plan view showing the tractor which, except as noted, is identical with that disclosed in my said pending application;

Fig. 2 is a section taken on the line $x^2 x^2$ of Fig. 1;

Fig. 3 is a detail in horizontal section on the line $x^3 x^3$ of Fig. 2; and

Fig. 4 is an end elevation of the tubular arm which is shown in section in Fig. 3.

Of the parts of the tractor, it is, for the purposes of this case, only desirable to particularly note the rear frame casting 1 having the forwardly projected tubular arm 4, which is preferably of heavy wrought iron or steel pipe rigidly secured at its rear end to the frame casting 1, and at its front end rigidly secured to a front wheel bearing bracket 5, to the prongs of which a relatively small front guide wheel 9 is journaled. The rear traction wheels 3 are journaled on axially alined trunnions of the frame casting 1. The explosive engine, which is indicated, as an entirety, by the numeral 16, has its cylinder and bed casting rigidly secured to the frame casting 1, and,

as shown, is a two-cylinder opposed engine with the axes of its cylinders extended in a forward and rearward direction. This engine drives the traction wheels 3 through suitable transmission mechanism, not necessary for the purposes of this case to consider, but which are fully described in my said pending application, but which, however, constitute no part of the present invention. The parts so far indicated by the numerals are indicated by corresponding numerals in my said pending application.

Coming now to the feature of my invention, it will be noted that the exhaust ports from the two cylinders of the engine are connected directly to branch pipes a and a^1 , which unite in a common exhaust pipe a^2 that taps and opens into the rear portion of the tubular arm 4. The front end of the said tubular arm 4 is partly closed by a perforated head b , which, as shown, is held in place by a long nut-equipped rod c that will extend through the closed rear end head of the said tubular arm.

It will thus be seen that the tubular arm 4, in addition to its primary function wherein it serves as a main frame member, also serves as an efficient muffler of large capacity. By this arrangement, not only is the construction of the tractor simplified and reduced in cost, but the ordinary attached muffler, which is always more or less in the way, is entirely done away with.

It will be noted that the engine is supported entirely upon the frame casting 1, and that the tubular arm 4 projects forward therefrom. The engine being located directly upon the frame casting 1, substantially all of its weight is taken directly by the traction wheels through the journals on the frame casting. The tubular arm 4, therefore, is not required to support the engine, but it serves as a reach connecting the frame casting 1 with the support for the steering wheel, and it also serves as a muffler receiving the exhaust from the engine. Being located in front of and being entirely independent of the engine or motor, it is not subjected to the heat that is generated by the motor and transmitted by the motor frame. There is a marked advantage in this construction over a construction in which the motor or engine is located upon a tubular frame that serves as a muffler. In

my construction the tubular arm does not serve as the motor frame but as an independent reach and muffler.

What I claim is:

- 5 1. The combination, in a tractor, of a rigid frame provided with axially aligned trunnions at its opposite sides, traction wheels journaled on said trunnions, a tubular arm having its rear end rigidly secured 25 to said frame and projecting forwardly therefrom, a steering wheel connected with and supporting the forward end of said arm, an explosive engine mounted upon said frame and substantially counter- 30 balanced upon said wheel trunnions, and exhaust pipes extending from said engine and connected with the rear portion of said tubular arm, whereby said arm serves as a reach for said tractor and as a muffler for its engine, substantially as described. 35
- 10 2. The combination, in a tractor, of a rigid frame casting provided with axially aligned trunnions at its opposite sides, trac- 20

tion wheels journaled on said trunnions, a tubular arm having its rear end rigidly secured to said frame at one side thereof and projecting forwardly therefrom, a steering wheel connected with and supporting the forward end of said arm, said wheel being in substantial alinement with one of the said traction wheels, an explosive engine mounted upon said frame and substantially counter- 25 balanced upon said wheel trunnions, and exhaust pipes extending from said engine and connected with the rear portion of said tubular arm, whereby said arm serves as a reach for said tractor and as a muffler for its engine, substantially as described.

In testimony whereof I affix my signature in presence of two witnesses.

RALPH B. HARTSOUGH.
